UNITED STATES PATENT OFFICE

135,413

DESIGN FOR A BREAD SLICING BOARD

Arthur R. De Long, Chicago, Ill.

Application February 13, 1943, Serial No. 109,537

Term of patent 3½ years

To all whom it may concern:

Be it known that I, Arthur R. De Long, a citizen of the United States and a resident of Chicago, in the county of Cook and State of Illinois, have invented a new, original, and ornamental Design for a Bread Slicing Board, of which the following is a specification, reference being had to the accompanying drawing, forming a part thereof, and in which:

Fig. 1 is a perspective view of a bread slicing board, showing my new design;

Fig. 2 is a top plan view of the same at slightly larger scale; and

Fig. 3 is an end elevational view of the same as seen from the right in Fig. 2.

I claim:

The ornamental design for a bread slicing board, as shown.

ARTHUR R. DE LONG.
